UNITED STATES PATENT OFFICE.

FRANCIS L. HORSPOOL AND SIDNEY C. RASMUSSEN, OF SALT LAKE CITY, UTAH, AS
SIGNORS, BY MESNE ASSIGNMENTS, OF TWO-THIRDS TO SAID HORSPOOL AND ONE-
THIRD TO SAID RASMUSSEN.

GAME OF SKILL.

Application filed November 29, 1926. Serial No. 151,354.

This invention relates to an improvement in a game of skill to be played in homes or business houses.

The main object of this invention is to provide a game played with a rod and a ball, whereby the ball is rolled back and forth on the rod and then dropped off the rod by the player thereof into a pocket below the rod.

10 The game is played with one or more rods and five or more balls. In the specification it will be described as played with one rod and five balls, the balls to be dropped off the rod into a plurality of pockets which

15 may be one row or many rows of pockets.

When used in a business house a vending or money receiving attachment is placed thereon whereby one wishing to play the game must place a coin into the vending attachment before he can receive the balls to play the game.

With these and other objects in view the invention consists of certain novel features of construction as hereinafter fully described and claimed.

In the accompanying drawing forming a part of this specification and in which corresponding parts are denoted by like reference characters, is illustrated the preferred form of embodiment of the invention capable of carrying the same into practical operation, it being understood that the invention is not necessarily limited thereto, as various changes in the shape, proportions and general assemblage of the parts may be resorted to without departing from the principles of the invention or sacrificing any of the advantages, and the right is therefore reserved for making all changes and modifications 30 which will fairly fall within the scope of the invention and claims made therefor.

Referring to the drawings:

Figure 1 is a front view of the invention with a vending or money receiving attachment thereon.

Fig. 2 is a side or end view of Fig. 1.

Fig. 3 is a view on line 3—3 Figs. 1 and 2.

Fig. 4 is a side or end view of the invention showing only one row of pockets therein.

50 Fig. 5 is a view on line 5—5 Fig. 4.

Fig. 6 is a view on line 6—6 Fig. 1 showing groove of the rod and ball resting therein.

The invention comprises a casing A the ends thereof having a slot 2 or 2' therein and

the front and back thereof has a glass face 55 3 and 3' thereon which is held in place by cleats 4. A rod 5 is placed through the slots 2 or 2' having a handle 6 on one end and a washer 7 on the other end. The rod 5 has a groove 8 therein in which a ball 9 is roller from one end of the rod to the other end. The handle 6 and the washer 7 prevent the rod being taken out of the slots.

Secured within the casing are a plurality of pockets 30 and 30' which are placed under 60 the rod 5 in such a manner so when ball 9 is dropped off the rod it will enter one of the pockets.

At one side of the casing is hinged a bottom 10 and 10' for the pockets. On the side 70 of the casing is placed a vending money receiver B which may be of any standard make. When the money receiver is used the slide 11 thereof has an arm 12 thereon which is pivotally connected to a bell crank lever 75 13. The other end of the bell crank lever 13 is secured to one side of the bottom 10 Fig. 2. The bell crank lever 13 is fulcrumed at 14 to the side of the casing. This bell crank is only used when the money receiver is used. 80 A lever 15 is used for tripping the table when the game is played without the money receiver.

Projecting from the pockets are side walls 16 which prevent the ball falling past the 85 table and also causes the ball to roll into one of the pockets if it should fall away from the pockets.

Below the pockets and within the casing is placed a chute 17 in which the ball 9 falls 90 when the bottom is lowered to allow the ball to drop out of the pocket. At the outlet of the chute is placed a bin 18 in which the ball rolls to be taken out of the casing.

In the operation and playing of the game, 95 if played in a home, handle 15 is raised to allow the balls to drop out of the pockets into the chute and then into the bin. They are now taken out by a player one of the balls being placed in the groove on rod 5 by 100 the player, the player selects a pocket in which he wishes to drop the ball, then holding the handle of the rod rolling the ball in the groove on the rod until it comes to where the player thinks he can hit the hole of his selection, then turn rod so ball will drop off at this point and repeat until the five balls have been played. That is when the single 105

row of pockets are used as shown in Figs. 4 and 5. When the pockets shown in Fig. 3 are used the game is played as follows.

There being five rows of pockets, each row 5 contains the same numbers, the numbers being staggered so they will be scattered in such a manner that no two numbers of the same numeral will be in the same horizontal line. In playing this game with these 10 pockets a certain number is given, for illustration we will use the numeral 25. In this case the player to win must drop a ball in all five pockets containing the numeral 5 which when added equals 25. It makes no difference 15 what number is the total the ball must drop into a pocket in each row to win. If the ball should drop in a row that has another ball therein the second ball will not count of it does drop on to the same number. 20

In the drawing Fig. 3 are shown five pockets horizontally and nine pockets longitudinally there may be many more pockets added according to the size of the game.

25 When the game is played with the money slot thereon, a coin is placed into the slot 20 handle 21 is now moved to push the coin through the chute 22 and to move arm 12 which operates the bell crank lever to lower 30 the bottom of the pockets so that all balls therein will drop out so the player can receive them and then the game is played as above stated.

Having thus described the invention what 35 we claim as new and desire to secure by Letters Patent, is;

1. A game of skill comprising a casing, a coin controlling slot on said casing, pockets within said casing, a gate for said pockets, means connected to said gate and to said coin controlling slot for opening and closing said gate, a rod extending through said casing, said rod having a groove thereon, a ball to roll to and fro in said groove, said rod being rotatably, slidably and tiltably mounted within said casing, and means for holding said rod within said casing. 40

2. A game of skill comprising a casing, a coin controlled means secured to said casing, a rod extending through said casing having a groove thereon in which a ball is rolled, said rod being slidably, tiltably and rotatably 45

55 mounted within said casing, pockets within said casing below, said ball to be dropped into one of said pockets when said rod is rotated, in the dropping of said ball it will fall into one of said pockets, a gate to hold said ball within said pocket, means connected to said gate and to said coin controlled means for opening and closing said gate, said ball 60 rolls from said pocket in the opening of said gate and means to allow said ball to roll from said casing.

3. A game of skill comprising a casing, a coin control secured to said casing, pockets within said casing into which balls are dropped, a gate for holding said balls in said pockets, means connected to said gate and to coin control for opening said gate to allow said balls to roll out of said pockets 70 when a coin is dropped into said slots, means in said slot for operating said coin to open said gate, a rod extending through said casing having a groove thereon, said rod being slidably, tiltably and rotatably mounted in said casing, said balls to be rolled to and fro in said groove in the tilting of said rod and to be rolled out of said groove in the rotating of said rod and to fall into said pockets and means in said casing to allow 75 said balls to pass out of said casing.

4. A coin controlled game of skill comprising a casing, a slidably, tiltably and rotatably rod mounted within said casing, said rod having a groove thereon in which balls are rolled to and fro in the tilting thereof and to be dropped off said rod when said rod is rotated and means for receiving said balls when said balls are dropped off said rod all 80 substantially as set forth. 85

5. A game of skill comprising a casing, a rod slidably tiltably and rotatably mounted in said casing and extending through said casing, said rod having a groove thereon in which balls are rolled in the tilting thereof, said casing has pockets therein and placed in such a manner that when balls are dropped off said rod they will fall into a pocket, means for holding said balls in said 90 pockets, means for letting the balls out of said pockets, and means for letting the balls out of said casing. 95
